UNITED STATES PATENT OFFICE

CARL MIEDBRODT, OF BERLIN-ROSENTHAL, GERMANY

AUTOMATIC REVERSING DEVICE

Application filed September 11, 1929, Serial No. 391,946, and in Germany October 27, 1928.

This invention relates to automatic reversing devices, for controlling periodically-operated gas-producers and for similar purposes, of the type in which change-over valves 5 are periodically reversed by control pistons or like elements operable by a pressure fluid.

According to the invention, I provide automatic reversing devices of this type, characterized by the fact that the piston or like 10 control element is reversible by periodic adjustment of one or more movable directioning tubes or other conduits through which the pressure fluid for operating the said piston or like element, is discharged.

15 Preferably, the discharge tube or other conduit is springy or flexible and the amount of adjustment of the discharge tube or other conduit may be limited by stops so as to fix its end positions with precision.

20 In a preferred embodiment of the invention, a tube or other conduit, or each of a number of such tubes or conduits, is supported by a pair of levers operable by control cams in such a manner that the said tube or other 25 conduit is set alternately in front of two openings communicating with the opposite ends of a cylinder containing a balanced control piston adapted to control the passage of a pressure fluid to and from a second cylinder 30 which contains a piston connected with a change-over valve.

An embodiment of the invention as applied 25 to the change-over valve of a periodically operating gas-producer will now be described with reference to the annexed drawing, which is, a diagrammatic elevation partially sectioned of the said embodiment.

In the drawing, the reference numeral 1 40 denotes the change-over valve of the gas-producer (not shewn.) This valve is connected with the piston 2a by a piston rod 2b. The cylinder 2 in which the piston 2a operates communicates by means of a pipe 4 with a control cylinder 3 and also communicates by means of a pipe 5 with a pressure accumulator 6. By means of a pipe 7 the control cylinder 3 communicates with the accumulator 6 and a pipe 8 connected to the cylinder 3 with a return fluid tank 9. The pressure fluid is fed to the accumulator 6 through

a pipe 11 by a pump 10. Within the control cylinder 3 a balanced piston 12 is arranged, the said piston being reduced in diameter at the middle as shewn.

Outside the control cylinder 3 is arranged 55 a flexible tube 13 which if desired may be of a springy nature. The nozzle 14 is fitted to the end of the tube 13 directed towards the cylinder 3 whilst the other end of the tube 13 is made of a coiled form and communicates 60 with the accumulator 6 by way of a receiver 15 and supply tube 16.

A uniformly rotated shaft 18 is located 65 above the springy or flexible tube 13 and has mounted thereon a pair of cams 17 upon which bear respectively a pair of levers 19 and 20 held together so as to make close contact with the aforesaid cams by a spring 21. To the levers 19 and 20 are connected respectively a pair of links 22 and 23, the lower end 70 of which embrace as shewn a springy or flexible tube 13.

The above described reversing device operates as follows:

In order to limit the movement of the tube 13 stops 27 and 28 are provided whilst draw-off pipes 29 are provided for the flow of fluid from the chamber into which the tube 13 projects, back to the tank 9.

As the shaft 18 and the cams 17 thereon rotate at uniform speed, the lever 19 and the cams 20 are each caused, in the course of each revolution, to move abruptly inwards towards the axis of the cams, this being effected by the spring 21 each time the step on either of the cams 17 comes into register with a lever 19 or the lever 20 as the case may be.

The movements imparted by the cams 17 to the levers 19 and 20 are transmitted to the springy tube 13 through the links 22 and 23 90 respectively and the nozzle 14 is thereby brought into position facing either the lower or upper control port of the cylinder 3. The pressure fluid issuing from the nozzle 14 finds its way to either one side or the other of the piston 12 according to the position of the said nozzle so that the piston is driven towards its corresponding end position. In this manner the reversal of the change-over valve 1 95 is initiated.

In the drawing the piston 12 is shewn at the upper end of the cylinder 3 and in this position pressure fluid is admitted from the accumulator to the upper side of the piston 2a in the cylinder 2 through the pipes 7 and 4, thereby closing the valve 1. When the nozzle 14 is moved upwards so as to face the upper port of the cylinder 3 the piston 12 is moved to its lowermost position and as a result the pressure in the upper part of the cylinder 2 is relieved by the escape of fluid to the pipes 4 and 8. Since the lower part of the cylinder 2 is in communication with the accumulator 6 by way of the pipe 5, the piston 2a and valve 1 is accordingly reversed. It will thus be apparent that in one end position of the balanced piston 12 the upper side of the piston 2a is subjected to pressure whilst in the other end position of the piston 2a this pressure is relieved. It will also be apparent that when the springy tube 13 moves upwards the piston 12 moves downward and vice-versa.

Instead of the piston 2a being operated by a liquid it may be operated by steam, air or gas; or, alternatively, in cases where the pressure fluid for operating the piston 2a is not the same as that used for the operation of the piston 12, the pressure fluid necessary for the reversing operation is supplied to the pipe 13 by a separate pump device.

Various modifications may be made in the reversing device without departing from the scope of the invention. For example, the control piston 12 may be provided with a piston rod which projects outwards from the head of the cylinder 3 in order that the movement of the said control piston can be effected by hand in the event of a break-down.

I claim:—

1. Automatic reversing devices comprising the combination with change-over valve means and operating mechanism therefor, of a control element movable in opposite directions by pressure fluid, tubular directioning means for directing pressure fluid for operation of said control element, means for supplying said directioning means with said pressure fluid, a uni-directional driving member, cam means on said member, tappet means operable by said cam means, and means for operatively connecting said tappet means with said directioning means so as to cause said pressure fluid to act intermittently on said control element in opposite directions alternately.

2. Automatic reversing devices comprising the combination with change-over valve means and operating mechanism therefor, of a control piston movable in opposite directions by pressure fluid, a directing nozzle for directing pressure fluid for operation of said control piston, means for supplying said directing nozzle with said pressure fluid, a uni-directional driving member, cam means on said member, tappet means operable by said

cam means, and means for operatively connecting said tappet means with said directing nozzle so as to cause said pressure fluid to act intermittently on said control piston in opposite directions alternately.

3. Automatic reversing devices comprising the combination with change-over valve means and operating mechanism therefor, of a control element movable in opposite directions by pressure fluid, tubular directioning means for directing pressure fluid for operation of said control element, means for supplying said directioning means with said pressure fluid, operating means for said directioning means whereby said pressure fluid is made to act periodically on said control element in opposite directions alternately, and stops for limiting the amount of movement of said tubular directioning means.

In testimony whereof I affix my signature.

CARL MIEDBRODT.
